TOASTER AND BROILER COMBINATION

Donald J. Booty, Chicago, Ill., assignor to The Proctor-Silex Corporation, Hartford, Conn., a corporation of Connecticut

Filed Mar. 18, 1960, Ser. No. 59,790

Term of patent 14 years

(Cl. D81—10)

FIG. 1 is a perspective view of the toaster and broiler combination embodying my new design;

FIG. 2 is a front elevational view thereof; and

FIG. 3 is an end elevation thereof, the tray handle being broken away for convenience of illustration only.

The remote unseen edges of the end members are mirror images of the corresponding edges of the end members shown in the drawing.

The dominant features of my design are shown in solid lines to characterize the end members and the open handle merging into the end members near the tops thereof and within the overhanging top flange portion.

I claim:

The ornamental design for a toaster and broiler combination, substantially as shown and described.
